Des. 212,580
Patented Nov. 5, 1968

212,580

CEREAL BASE COOKED FOOD SNACK

Philip M. Sautier, Minneapolis, and Gordon H. Wells, Jr.,
Hopkins, Minn., assignors to The Pillsbury Company,
Minneapolis, Minn., a corporation of Delaware

Filed Dec. 5, 1967, Ser. No. 9,635

Term of patent 14 years

(Cl. D1—11)

FIG. 1 is a front perspective view of a cereal base cooked food snack showing our new design;

FIG. 2 is a rear elevational view; and

FIG. 3 is an end elevational view thereof.

We claim:

The ornamental design for a cereal base cooked food snack, as shown.
